UNITED STATES PATENT OFFICE.

ROY T. WALASKE, OF MILWAUKEE, WISCONSIN.

DESIGN FOR A SMOKER'S TRAY.

Application filed August 25, 1928. Serial No. 27,961. Term of patent 14 years.

To all whom it may concern:

Be it known that I, Roy T. WALASKE, a citizen of the United States, residing in the city of Milwaukee, county of Milwaukee, and State of Wisconsin, have invented a new, original, and ornamental Design for a Smoker's Tray, of which the following is a specification, reference being had to the accompanying drawing, forming part thereof.

I claim:

The ornamental design for a smoker's tray, as shown.

In testimony that I claim the foregoing I have hereunto set my hand at Milwaukee, in the county of Milwaukee and State of Wisconsin.

ROY T. WALASKE.
